[57] CLAIM

The ornamental design for a combined dispenser and brush attachment for a shaving cream container or the like, substantially as shown.

DESCRIPTION

FIG. 1 is a top perspective view of a combined dispenser and brush attachment for a shaving cream container or the like showing my new design;

FIG. 2 is a bottom perspective view;

FIG. 3 is a top plan view;

FIG. 4 is a side elevational view;

FIG. 5 is an end elevational view; and

FIG. 6 is a bottom plan view.
